DESIGN FOR A PANTIE

Julia Lufty Sarge, New York, N. Y.

Application December 31, 1941, Serial No. 104,937

Term of patent 7 years

To all whom it may concern:

Be it known that I, Julia Lufty Sarge, a citizen of the United States, residing at New York, in the county of New York and State of New York, have invented a new, original, and ornamental Design for Pantie, of which the following is a specification, reference being had to the accompanying drawing, forming part thereof.

Fig. 1 is a front elevation of a pantie showing my design; and

Fig. 2 is a rear elevation thereof.

The pantie is characterized by a two-piece front portion in which the material forming the front of each leg extends in an upwardly inclined direction across to the opposite side seam.

I claim:

The ornamental design for a pantie, as shown and described.

JULIA LUFTY SARGE.
